UNITED STATES PATENT OFFICE.

GEORGE WESLEY CHILDS, OF RIDGWAY, PENNSYLVANIA.

PROCESS OF CONCENTRATING LIQUIDS.

936,760.

Specification of Letters Patent. Patented Oct. 12, 1909.

Application filed December 30, 1903. Serial No. 187,094.

To all whom it may concern:

Be it known that I, GEORGE WESLEY CHILDS, of Ridgway, in the county of Elk and State of Pennsylvania, have invented 5 certain new and useful Improvements in Processes of Concentrating Liquids, whereof the following is a specification, reference being had to the accompanying drawings.

My improvements relate to processes of 10 vaporizing liquid while progressing it through a series of vessels, wherein a partial vacuum is maintained.

In apparatus of the class contemplated as heretofore constructed, the vessels are permanently connected with each other in an unchangeable sequence, so that a certain vessel 15 of the series is constituted the initial one, to which the weak liquid is always introduced, and another vessel is constituted the 20 terminal one, in which the liquid is always evaporated to greatest specific gravity and from which the liquid concentrate is finally discharged. Such an arrangement may be successfully employed for the concentration 25 of some syrups, but I find that during the process of concentrating other solutions, such as extracts of bark, and similar vegetable matters, in such an apparatus, the tubes in contact with the liquid in the vessels succeeding the first one in the series become 30 incrusted with deposits from the liquid, as the latter increases in specific gravity, and, as such deposits rapidly increase during the conduct of the process, the efficiency of the 35 apparatus as a whole is not only materially reduced, by the presence of such deposits, but the liquid concentrate is deprived of the matter deposited.

I have ascertained that the losses incident 40 to the deposit of a portion of the matter from the solution, as above noted may be obviated by shifting in rotation from one to another of the vessels in the series, the regions of introduction of the weak liquid and 45 of discharge of the concentrate; with the effect that the deposits made from the liquid of greater specific gravity are redissolved by the liquid of less specific gravity and all of the solid matter is discharged in solution in 50 the concentrate. Therefore, my improved process is of three-fold advantage, first, in that the maximum volume of production may be continuously maintained; second,

that all of the concentrate may be discharged in liquid form, and, third, that the cost of 55 maintenance of the apparatus is materially reduced, for, the deposits aforesaid can only be eliminated from the ordinary apparatus by renewing the tubes or other parts upon which they lodge. 60

My invention comprehends the various novel features herein set forth.

My improved process may be more clearly explained by reference to the accompanying drawings which show a multiple effect comprising four evaporating pans, so constructed and arranged with respect to a weak liquid inlet conduit and a concentrated liquid, discharge conduit, that any selected one of said pans may be constituted the 70 initial pan of the series in connection with the weak liquid conduit, and any selected one of said pans may be constituted the terminal pan of the series in connection with the concentrated liquid discharge conduit. 75 I also find it convenient to provide said apparatus with a vapor condenser and vapor pipes in such relation thereto that the vapors may be conducted to said condenser from which every one of the pans is, for the time 80 being, the terminal pan. Said apparatus also comprises other convenient adjunctive devices, but it is to be understood that I do not desire to limit myself to a series comprising any particular number of pans, or 85 to the employment of the particular adjunctive devices described; as various modifications may be made in the apparatus without departing from the essential features of my process. 90

In the drawings, Figure I, is a plan view of said apparatus, and Fig. II, is a side elevation thereof.

In said figures,—1, 2, 3, and 4, are the evaporating pans of the series conveniently 95 grouped around the vapor condenser 6. Said pans are connected with each other by counterpart vapor pipes 7, which extend from the upper vapor chamber 8, of one pan to the lower heating drum 10, of the next 100 adjoining pan. Said pipes 7, have counterpart branches 12, extending to the condenser 6. Communication between the adjoining pans by way of the pipes 7, is respectively controlled by valves 14, 15, 16, and 17, the 105 valve 14, controlling communication from

the pan 1, to pan 2. Communication between said pans and the condenser by way of the branch pipes 12, is respectively controlled by the valves 19, 20, 21, 22, the valve 5 19, controlling communication from pan 1, to the condenser.

The weak liquid which is to be concentrated is supplied through the inlet 24, to the conduit 25, which is connected with the 10 pans 1, to 4 inclusive, by the respective branches 27, 28, 29, and 30, the pipe 27, connecting with pan 1. Similarly said pans 1 to 4 inclusive are respectively connected by branches 32, 33, 34, and 35, with the concentrated liquid discharge conduit 37, which latter is provided with the outlet 38, leading to the pump 39. The introduction of the weak liquid from the conduit 25, to either of the pipes 27, 28, 29, and 30, selectively, in 15 accordance with which pan is for the time being the initial one, is determined by the valves 41, 42, 43, and 44. Likewise the final discharge of concentrated liquid through either of the pipes 32, to 35, selectively, in 20 accordance with which pan is for the time being the terminal one is determined by the valves 46, 47, 48, and 49, respectively. Moreover, the pipes 32, 33, 34, and 35, through which the liquid is discharged from the individual 25 pans, are respectively provided with branches 51, 52, 53, and 54, respectively extending to the inlet pipes 28, 29, 30, and 27, of the individual pans, and respectively controlled by valves 56, 57, 58, and 59, to determine 30 whether the liquid shall be discharged to the next adjoining pan, or to the concentrated liquid conduit 37. The weak liquid inlet pipes 27, 28, 29, and 30, of the respective pans 1, to 4, inclusive, are conveniently provided with regulators 61, 62, 63, and 64, respectively, by which the liquid in the respective pans may be automatically maintained at a predetermined level.

The heating drums 10, of the pans 1, to 4, 45 inclusive are respectively provided with condensation drain pipes 66, 67, 68, and 69, and, each of said condensation pipes is provided with four pipe connections respectively marked 71, 72, 73, and 74, and respectively controlled by valves 81, 82, 83, and 84. Said pipes 66, 67, 68, and 69, are differently connected, with the pipe 86, leading to the boilers; the pipe 87, leading to the left hand end of the water pump 88; the pipe 89, leading 50 to the right hand end of said pump 88, and, the drip pipe 90, leading to the hot well 91, shown in Fig. II. It may be here noted that the different connections of the similarly arranged sets of valves 81, to 84, inclusive, 55 which sets are respectively local to the condensation pipes 66, 67, 68, and 69, are found convenient with reference to the order in which they are opened, as hereinafter de-

scribed, in accordance with which one of the pans 1 to 4, is for the time being the 65 initial pan.

It is to be understood that the vapors arising from the liquid being concentrated in what are for the time being the first, second and third pans of the series, are respectively utilized to heat the tubes 11, in the drums 10, of what are for the time being the second, third and fourth pans in the series, wherein they are condensed and discharged as water through the pipes 67, 68, and 69. In order 75 that the drum 10, of whichever pan is the initial one may be heated, each of the vapor pipes 7, is provided with a steam inlet pipe 93. Said pipes 93, are respectively controlled by the valves 94, 95, 96, and 97; the 80 valve 94, controlling the inlet of steam to the pipe 7, connecting the pan 1, with the pan 2. Said pipes 93, are conveniently brought together in common connection with a high pressure steam inlet 98, and low pressure exhaust steam inlet 99, controlled by suitable valves. The vapors from what is for the time being the fourth pan of the series are delivered through its respective branch pipe 12, to the condenser 6, which is provided 85 with a drip outlet 100, extending to the hot well 91. Said condenser is also provided with the pipe 102, leading to a vacuum pump, so that the vaporization of the liquid in the last pan of the series may be facilitated. 95

When the pan 1, is to be used as the initial pan of the series, and the pan 4, as the terminal pan, the valves are set as follows:—The valve 41, controlling communication between 100 the weak liquid supply conduit 25, and the inlet pipe 27, leading through the regulator 61, to the pan 1, is opened; all of the other valves from said conduit 25, are closed; and, the valves 56, 57, and 58, controlling the 105 connections between the adjoining pans are opened; so that the liquid flows successively from the pan 1, through, pans 2, and 3, to pan 4, of course, increasing in specific gravity in its traverse. The concentrated 110 liquid is discharged from pan 4, through the pipe 35, and, the valve 59, being closed and the valve 49 being opened, said concentrate is delivered to the conduit 37.

The respective steam inlet valves 94, 95, 115 and 96, leading to the pans 2, 3, and 4, are closed and the steam inlet valve 97, leading to the pan 1, opened. The vapor valves 14, 15, 16, are opened and the vapor valve 17, shut; the valves 19, 20, 21, are shut and the 120 valve 22, opened. So that the liquid in the pan 1, is vaporized by the steam surrounding the tubes 11, containing it, and the vapors from pan 1, are delivered within the drum 10, of the pan 2, to again heat and 125 vaporize the liquid. The vapor from pan 2,

is delivered to the pan 3, wherein the liquid is again vaporized and the vapor delivered to the drum 10, of the pan 4. The liquid being again vaporized in pan 4, the vapors are delivered through the branch pipe 12, to the condenser 6, wherein they are condensed and flow through the pipe 100, to the hot well. All of the valves 81, are opened and the valves 82, 83, and 84, are 10 shut, with the effect that the condensation pipes 66, 67, 68, and 69, of the respective pans 1, 2, 3, and 4, are respectively connected with the boiler, the hot well, the right hand side of the pump 58, and the left hand side of said pump.

When the pan 4, is to be used as the initial pan of the series and the pan 3, as the terminal pan, the valves are set as follows:—The valve 44, controlling communication between the weak liquid supply conduit 25, and the inlet pipe 30, leading through the regulator 64, to the pan 4, is opened; all of the other valves from said conduit 25, are closed, and the valves 59, 56, and 57, controlling the connections between the adjoining pans are opened; so that the liquid flows successively from the pan 4, through the pans 1, and 2, to the pan 3. The concentrated liquid is discharged from the pan 3, through the pipe 34, and, the valve 58, being closed and the valve 48 being open said concentrate is delivered to the conduit 37. The respective steam inlets 97, 94, and 95, leading to the pans 1, 2, and 3, are closed, 35 and the steam inlet 96, leading to the pan 4, opened. The vapor valves 17, 14, 15, are opened and the vapor valve 16, shut; the valves 22, 19, and 20, are shut and the valve 21, opened. So that the liquid in the pan 4, 40 is vaporized, by the steam surrounding the tubes 11, containing it, and, the vapors from pan 4, are delivered within the drum 10, of the pan 1, and so on through the series; the vapors from the pan 3, being delivered 45 through the branch pipe 12, to the condenser 6.

In the last named operation, with the pan 4, as the initial member of the series, all of the valves 84, are opened and the valves 81, 50 82, and 83, shut, to effect the proper connections of the respective condensation pipes 66, 67, 68, and 69. Similarly when the pan 2, is the initial pan, all of the valves 82, are opened and the valves 81, 83, and 84, are 55 shut; and, when the pan 3, is the initial pan, all of the valves 83, are opened and the valves 81, 82, and 84 shut.

It is to be understood that each of the 60 pans of the series is thus in rotation constituted the initial member hereof, and the regions of introduction of the weak liquid and of discharge of the concentrate thus progressively shifted from one vessel to an-

other in the series, at such intervals as to insure the solution and discharge of all of 65 the involatile contents of the weak liquid in the concentrated liquid product.

Although I have described a form of evaporating pan wherein the liquid to be concentrated is disposed within tubes which are 70 surrounded by the heating medium, to wit, the vapors from the preceding pans or steam from an external source, it is to be understood that the method or means for heating the liquid is immaterial to my present invention. 75

I claim:—

1. The herein described process of concentrating liquid, which consists in progressing the liquid through a series of vessels; causing the liquid to vaporize during its progression; utilizing the vapor of said liquid from one vessel to heat another, successively in said series; and, shifting from one to another of said vessels, in rotation, the regions of introduction of the raw liquid and of discharge of the concentrate. 80

2. The herein described process of concentrating liquid, which consists in progressing the liquid through a series of vessels; causing the liquid to vaporize during its progression; utilizing the vapor of said liquid from one vessel to heat another, successively in 90 said series; separately discharging the vapor and concentrate; and, shifting from one to another of said vessels, in rotation, the regions of introduction of the raw liquid and of discharge of the concentrate. 95

3. The herein described process of concentrating a liquid in a series of evaporating 100 pans, through which the liquid is successively progressed while vaporizing; which consists in utilizing the vapor of said liquid from one vessel to heat another, successively in said series; and, successively constituting 105 each pan the initial pan of the series.

4. The herein described process of concentrating a liquid in a series of evaporating pans, through which the liquid is successively progressed while vaporizing; which 110 consists in utilizing the vapor of said liquid from one vessel to heat another, successively in said series; and, successively constituting each pan the terminal pan of the series.

5. The herein described process of concentrating liquid, which consists in progressing the liquid through a series of vessels, causing the liquid to vaporize during its progression; utilizing the vapor of said liquid from one vessel to heat another, successively in 120 said series and preventing said liquid from incrusting said vessels, by shifting from one to another of said vessels, in rotation, the regions of introduction of the raw liquid and of discharge of the concentrate. 125

6. The herein described process of main-

taining free from incrustation a series of evaporating pans, constituting a multiple effect, by constituting each vessel in succession the one from which the concentrate is discharged and the one to which the raw liquid is introduced.

In testimony whereof, I have hereunto

signed my name, at Philadelphia, Pennsylvania, this ninth day of December, 1903.
